UNITED STATES PATENT OFFICE.

DAVID LAZAR, OF BROOKLYN, NEW YORK.

VENDING MACHINE.

Application filed January 25, 1923. Serial No. 614,868.

My invention relates generally to coin controlled vending machines and more particularly to a device of this character which may be attached to the backs of theatre seats for the purpose of vending candy or other articles of similar character.

Vending devices of this type are generally provided with a very complicated coin controlled mechanism which requires considerable housing space, making the casing large and objectionable for use in restricted places such as the space between seats of a theatre. The principal object of the present invention is to provide a vending device which is comparatively small, and which carries a detachable plate upon which is compactly mounted the entire coin controlled mechanism.

Further objects of the invention are to provide the casing with two compartments containing the articles to be released by inserting coins in the respective slots for each compartment and to provide one operating mechanism for releasing separately the articles from both compartments.

A still further object of the invention is to provide means which will prevent a second coin from being inserted into the slot of an empty compartment.

The invention is fully disclosed in the following specification, particularly pointed out in the appended claims, and illustratively exemplified in the accompanying drawings, in which, Figure 1 is a perspective view of my improved device attached to the back of a seat and showing the pusher depressed and one packet released and depending from the bottom of the machine; Fig. 2 is a perspective view of the detachable plate and coin controlled mechanism, the lock and coin support being omitted; Fig. 3, is a perspective view of the casing or container with cover raised and detachable plate removed to show the compartments for the articles; Fig. 4, is a front elevational view of the vending machine with cover raised and the mechanism set as it would appear when the container is loaded; Fig. 5, is a view similar to Fig. 4 except that the mechanism is shown in tripped position and parts are broken away to more clearly disclose otherwise hidden parts; Fig. 6 is a substantially longitudinal section view through the device and taken on the line 6-6 of Fig. 4; Fig. 7 is a sectional view on the line 7-7 of Fig. 5; and Fig. 8 is a perspective view of one corner

of the plate showing the coin slot and coin stop device.

Referring to the drawing, 10 denotes the casing or lower compartment comprising a flat back wall 11 and longitudinal upright side walls 12, the lower ends of the latter being rounded, as shown in Figures 1 and 3. A longitudinally disposed central partition 13 is mounted integral with the casing 10 and the spaces on both sides of this partition form the compartments A and B into which the packages are placed as hereinafter described. The back wall 11 between the opposite walls of both compartments A and B is provided with inclined raised strips of material 14 extending from the upper edge to a plane short of the opposite or lower edge. The inclination of the strips 14 begins at zero at the upper edge of the back wall 11 and increases in height towards the lower ends and in a similar manner the outside edge of the partition 13 is inclined to be substantially parallel with the planes of the strips themselves. Adjacent the lower edge of the casing 10 and disposed at the ends of the strips 14 and on opposite sides of the partition 13 are a pair of trap delivery doors 15. The doors 15 comprise flat metal members having eyes 16 along their inside edges adapted to rotate about pivot pieces 17 formed by a series of cutouts 18 in the back wall 11. The doors 15 swing by gravity from a horizontal plane to a vertical depending position as shown in Figures 5 and 7. The inner faces of the doors 15 are provided with eyes 19 to receive hooking devices for facilitating the release of the doors from their horizontal or closed positions to enable them to swing to open positions.

The upper edge of the casing 10 carries a hinged cover casing 20 comprising a front wall 21, upright side walls 22 and top wall 23, the latter being provided with two coin slots 24 adjacent opposite side edges thereof. The lower ends of the side walls 22 are curved toward the rear and extreme lower edge of the cover, when held in closed position, projects to a plane coinciding with the lower faces of the doors when the latter are in closed position, as shown in Figure 6. The upper front edge of the cover 20 is provided with a cavity 25 formed by cutting out a central portion in both the front wall 21 and top wall 23, the depth of the cut in the latter wall corresponding to the plane

of the back wall of the coin slots 24, see Fig. 4. This cavity 25 is adapted to receive the finger operated plunger for operating the coin controlled mechanism.

5 The lower end of partition 13 extends above the outside edge thereof to provide a hook shaped member 26 and the walls 12 are provided with notches 27 cut to a depth coinciding with the plane of the outside edge 10 of the partition, the said notches being disposed about midway of the length of the walls. The outside edge of the partition 13 is further provided with raised supports 28 adjacent opposite ends thereof to receive the 15 plate 29 on which the coin controlled mechanism is mounted.

The plate 29 comprises a flat sheet of material having an upright flange 30 along its lower edge, the latter being provided with 20 a centrally disposed slot 31 which embraces the hook member 26, while the latter hooks over the face of the plate itself to hold it in position. To further hold the plate 29 in position against the supports 28 the 25 side edges of the plate are provided with projections 32 which are adapted to register with the notches 27, as shown in Figures 4 and 5. The lower edge of the plate 29 adjacent opposite side edges is provided 30 with notches 33 which are aligned with and open into similar notches 34 disposed in the inside edge of the flange 30, the notches 33 and 34 on both sides being adapted to receive the eyes 19 of the doors, as shown in Fig. 4. 35 The notches 34 open into slots 35 in the flange 30, the said slots 35 projecting toward the center line of the plate.

The coin controlled mechanism for releasing the doors 15 comprises a Y-shaped coin receiving arrangement composed of two separate chutes 36 and 37, the receiving upper ends being adapted to register with the coin slots 24 in the cover 20. It will be apparent 40 from the drawings that both sets of coin actuating mechanisms are identical in construction with the exception that one set is right hand and the other is left hand, so that a description of but one set will suffice for both. Referring to the left hand set the chute 36 comprises a channel shaped member the upper end of which is secured along its open side to the plate 29. The upper portion of the chute 36 is parallel 45 with the side edge of the plate 29 for a short distance and then inclined downwardly towards the central line of the plate. At this point the two chutes 36 and 37 are brought 50 into close proximity with each other where they then project downwardly and parallel to a plane about midway of the length of the plate. The faces of both chutes are provided with open ended slots 38 having cam surfaces 39 at their upper ends. The cam 55 60 65 surfaces 39 terminates at a point coinciding with the periphery of a coin X after the latter has

been inserted into a coin slot 24 and permitted to fall through the chute 36 to a point where it is held to be projected against the coin actuated mechanism.

The stops for the coin in this position consist on one side of a roller 40 which is disposed on the central line of the plate at the lower ends thereof where the opposite sides of the roller overlie the delivery ends of the chutes, so that one roller suffices for both. 70 The stop on the opposite side of the coin path for the door releasing arrangement consists of a roller 41 mounted on a lever 42. The lever 42 is disposed flat against the plate 29 and provided with a screw pivot member 43 carried by the plate. The lower end of the lever 42 is provided with a hook toe 44 which moves through the slot 35 and eye 19 of the door 15 to hold the latter closed. The normal position of the lever 42 is towards the locked position, as shown in Fig. 4, and the parts are held in such position by the spring 45 opposite ends of which are secured to pins carried by the plate and lever, respectively. Between the spring 45 and pivot 43 the lever carries a stop pin or screw 46 against which the notched end of a detent 47 is adapted to engage, the detent being pivotally mounted at the side edge 85 of the plate and adapted to fall by gravity into position against the pin after the lever has been swung inwardly. The upper end or arm of the lever 42 is raised by an inclined portion to a plane above the surface of the plate 29 and just above the face of chute 36. 90 The roller 41 is mounted beneath this raised portion at the end thereof. Beyond the roller 41 and secured to the lever 42 is a flexible strip of material referred to hereinafter as the coin stop, 48. The stop projects upwardly and over the chute 36 to the mouth of the latter where it is provided with rearwardly directed cam portion 48' in the shape of a quadrant, the high point of the latter being directed towards the side edge 100 of the plate and in normal position resting against the surface of the chute 36. At the point against which the high point of the cam 48' is said to rest in normal position, i.e. 105 when the lever is set to be acted upon by a coin, the upper edge of the chute 36 is cut away to provide a slot 49 through which the cam moves to a position across the coin path 110 in the chute. The flexible nature of the stop 48 makes it possible for the cam portion to ride into and out of the coin path by merely 115 rocking the lever in one direction or the other, as shown in Figures 4 and 5. When the cam is disposed across the coin path it 120 will be engaged beneath a catch or hook member 50 which will prevent the coin stop from being forced out of the slot.

The coins are projected from the chutes 36 and 37 and against the rollers 40 and 41 by means of a pair of pivoted detents 51,

the latter being carried by the cross head of a T shaped slide bar 52. The nose of each detent is adapted to move through the slot 38 and against the periphery of the coin X, and when in normal position the nose is supported on the cam surface 39 and out of the path of the travel of the coins through the chute. The stem portion of the T-slide 52 is guided in a channel piece 53 superposed on the faces of the chutes 36 and 37, the axis of the piece 53 and stem being in the general longitudinal direction of the center line of the plate. The stem projects upwardly beyond the piece 53 to receive the finger 15 plunger 54 which actuates in the cavity 25 and which consists of an angular member, the longer arm being disposed parallel to and against the inside face of the front wall of the cover while the lateral arm forms the 20 finger plate and is disposed parallel to the top wall of the cover. The plunger is yieldably supported in its upper most position by a pair of springs 55 attached at their lower ends to the cross head of the T slide bar 52 25 and at the upper ends to pins 56 secured to the inclined walls of the chutes.

The cover member 20 is locked to the plate 29 by means of suitable locking device designated generally as 57, which is provided with 30 a key slot 58 projecting through an opening in the front wall 21 of the cover 20. Just above the locking device is a coin holder 58 to support the coins from the chutes and to prevent the coins from becoming engaged 35 with parts of the mechanism. The holder comprises an upright curved wall integral with the plate 29 and disposed between the two levers 42 at a point level with the pivots therefor, and a central partition wall on opposite sides of which the coins are collected 40 from the chutes.

The operation of the vending device is as follows: Assuming a coin is dropped into the left hand slot, as shown in Fig. 5, and 45 the plunger 54 depressed, the T head will move downwardly with the detents 51. The left hand detent 51 will ride over the cam surface 39 and into the slot 38 and against the periphery of the coin which will be 50 forced downwardly against the rollers 40 and 41. The roller 40 throws the coin against the roller 41 to swing the lever 42 about its pivot, whereupon the hooked toe 44 of the lever will move out of the eye 19 and into the slot 35 and the door 15 will drop to open position as shown in figures 5 and 7. The package Y contained in the compartment A is ejected by means of a spring actuated plate 59 consisting of a fixed portion 60 integral with the back of the plate 29, a coiled spring 61 depending therefrom and a packaging plate 62 supported at the end of the spring. The plate 29 carries two 55 of these ejectors one for each compartment. It will be apparent that the package must

rest against the inclined surface 14, as shown in Figure 6, and when the door 15 is released the package will be forced downwardly and outwardly away from the back wall 11 to avoid becoming engaged by the edge of the door itself. 70

Simultaneously with this operation the lever 42 has moved so as to bring the coin stop into the mouth of the chute, as previously described whereupon the detent 47 will 75 have engaged to stop pin 46 and locked the lever in position. The plunger 54 is released and moves back to its normal position so as to be in position to act when a coin is placed in the other slot. 80

It will be noted that in order to reload a machine all that is necessary to do is to unlock the cover 20, raise the latter and detach the plate 29 whereupon the compartments are exposed and ready to receive a new 85 charge. After replacing the plate the detent 47 is lifted and the lever 42 and coin stop 48 will swing to their initial positions. In moving to its initial position the curved edge of the cam 48' will engage against the edge of the slot 49 and cause the flexible coin stop 48 to bend slightly, as shown in Fig. 2. The cover 20 may then be replaced and the latter locked. The mounting of all 90 of the mechanism on the plate 29 and then making the plate removable aids greatly in making repairs because when a machine is found to be not in working order it is simply necessary to replace the old plate by a new one, several of which may be carried by the 95 refilling operator. 100

Having described my invention what I claim is:

1. In a vending machine, a container having a hinged cover member at one end and delivery openings at the other end, hinged doors for each delivery opening, a detachable longitudinally disposed partition plate arranged within the container and forming a chamber for the articles to be sold and a second chamber to receive coins, and coin actuated mechanism carried by the plate in the coin chamber for releasing the said doors to discharge the contents of the chamber on the opposite side of the plate. 105 110 115

2. A vending machine, as claimed in claim 1, in which the plate is provided with coin chutes to conduct the coins to the coin actuated mechanism, and a coin stop carried by said mechanism and movable into the opening in the chute to prevent the insertion of a second coin into the chute of an empty container, substantially as described. 120

3. A vending machine, as claimed in claim 1, in which the plate is provided with coin chutes to receive and guide the coins to the said coin actuated mechanism, and means operating against coins inserted in the chutes to actuate the said mechanism, substantially as described. 125 130

4. A vending machine, as claimed in claim 1, in which the coin actuated mechanism comprises a pivoted lever having a hook at one end to engage a door of the container, and a contact member carried by the lever and movable across the path of travel of the coin, whereby pressure exerted against the coin will rock the said member and the lever to withdraw the said hook and release the door, substantially as described.
5. A vending machine, as claimed in claim 1, in which the said plate is provided with a plurality of coin chutes, to receive and guide the coins to the coin actuated mechanisms, the latter comprising a pivoted lever adjacent each chute and having a hook at one end to engage a door of the container, a contact member carried by the lever and disposed at the mouth of the chute in the path of travel of a coin, and a coin stop carried by the opposite end of said lever and movable into the opening in the chute to prevent the insertion of a second coin into the corresponding chute of an empty container, substantially as described.
6. A vending machine, as claimed in claim 1, in which the said partition plate carries all of the operating mechanism, and the container is provided with means for engaging the plate to hold it in position within the vending machine, substantially as described.
7. A vending machine, as claimed in claim 1, in which the partition plate is provided with a slotted angular portion substantially parallel with the said doors in closed position, a partition to divide the said container into compartments, and a projecting piece at the end of the last named partition having a notch to receive the edge of the said plate and a portion to insert into the said slot in the angular portion thereof, substantially as described.
8. A vending machine, as claimed in claim 1, including coin chutes disposed on the plate, the said chutes being provided with forked delivery ends, and means movable into the space between prongs of the said delivery ends to engage the coins and press the latter against the coin actuated mechanism, substantially as described.
9. A vending machine, as claimed in claim 1, including coin chutes disposed on the plate, the mouths of the chutes being closely adjacent the opposite ends of the plate, the mid portion of the chutes being inclined downwardly toward each other and terminating at the delivery ends in closely adjacent parallel pieces having slotted openings, and means for ejecting the coins from the delivery ends to effect the operation of

the coin actuated mechanism, substantially as described.

10. A vending machine, as claimed in claim 1, including coin chutes disposed on the plate having slotted delivery ends, and means for ejecting the coins from the chutes comprising a slide bar movable over said chutes and provided with openings coinciding with the slots in the coin chutes, and pivoted detents mounted in the said openings and movable into and out of the said slots to engage against the coins inserted in the chutes to eject the latter therefrom and against the coin actuated mechanism, substantially as described.

11. A vending machine, as claimed in claim 1, including a pair of coin chutes mounted on the said plate, the delivery ends of said chutes being provided with open ended slots, a guide plate carried by the chutes, a slide bar extensible in said guide plate and provided with lateral projections to overlie both slots in the chutes, detents pivotally mounted in the projections and adapted to operate against coins in the chutes, and springs connected to said slide to normally support the slide in upward position, whereby the detents are held at the edges of said slots, substantially as described.

12. In a coin controlled vending machine, a container, a detachable partition plate within said container forming separate article and coin chambers, delivery doors through which the contents of the machine are to be discharged, means carried by the plate for guiding the coins from the outside into the interior, means for simultaneously releasing said doors and closing the guiding means, and means for projecting the coin against said means to actuate the latter for releasing the doors.

13. In a coin controlled vending machine, a container, a detachable partition plate within said container for receiving the coins and forming separate article and coin chambers, releasing means for the contents of the machine mounted on the plate and actuated by movement of the coin into engagement therewith, means for locking the releasing means in releasing position, resilient means carried by said releasing means for preventing a subsequent coin to be inserted after the contents have been discharged and delivery doors for said container.

In testimony whereof, I, David Lazar have signed my name to this specification, this 20th day of January 1923.

DAVID LAZAR.
